YARN SKEIN DYEING APPARATUS

Leslie L. Walmsley, Swarthmore, Pa., assignor to American Viscose Corporation, Philadelphia, Pa., a corporation of Delaware

Filed Mar. 6, 1957, Ser. No. 644,401

3 Claims. (Cl. 68—206)

The present invention primarily relates to processing apparatus for use in the liquid treatment of skeins of filamentary yarn or other filamentary material temporarily or permanently maintained in convolute form.

Liquid dyeing of skeined filament yarn constitutes a large segment of the textile industry. There are a number of inherent problems as yet to be overcome in this field. For instance, it has been found to be extremely difficult to obtain a level shade dyeing of the filaments within the skein because of the necessity of the quick dyeing time used in these processes in order to meet production schedules. In addition, the equipment or apparatus now in use for effecting the liquid treatment of the yarn skeins causes the skeins to become snarled or the filaments to be drawn or even broken as a result of the cascade of hot dye liquor being forced under high pressure through the coiled yarn filaments of the skeins. These disadvantages brought about in the dyeing of the skeins cause further trouble in the later winding of the yarns onto spools and bobbins.

With the use of present dyeing equipment, it has been also found that the resultant yarn of the skeins has a white specky condition especially in the heavy denier yarns when dyed with vat colors. In order to overcome this condition, the dyer must use lengthy and expensive processes which cause further winding problems and increase in costs.

It is therefore one object of my invention to provide a novel and improved liquid dye processing unit for use in dyeing filament yarn skeins wherein the above disadvantages may be overcome.

Another object of my invention is to provide a novel and improved liquid dye processing unit for use with yarn skeins wherein an impermeable or non-absorbent, flexible type sleeve is used which is positioned over the exterior of the yarn skeins and wherein the inner portions of the 50 yarn skeins remain exposed.

Another object of my invention is to provide a novel and improved skein cover consisting of an impermeable, flexible sleeve wherein the material used to form the sleeve has the properties of being resistant to hot mild acids and strong hot alkali solutions as well as inert to dyes and resistant to becoming gummy or sticky as a result of the chemicals used in the processing operation.

Still another object of my invention is to provide a novel and improved skein cover consisting of an impermeable, flexible sleeve wherein the sleeve has inwardly tapering skein retaining ends.

Another object of my invention is to provide a novel and improved skein cover consisting of an impermeable, flexible skein cover which is made from a fusible material.

A final object of my invention is to provide a novel and improved skein cover consisting of an impermeable, flexible skein cover formed of a fusible sheet material which is joined at its ends by a fusible seam.

Other objects and advantages of my invention will become apparent from a study of the following description and drawing wherein:

Figure 1 is a perspective of my liquid treating apparatus for the processing of yarn skeins; and

5 Figure 2 is a section taken along lines II—II of Figure 1 and shows the skeins and cover in rest position on the dye tube.

Referring now to the drawing, my skein liquid processing apparatus includes a container 1 for holding suitable processing liquid or dye liquor for the yarn skeins. Positioned directly above the container 1 is a perforated tube or dyeing arm 3 which supports a plurality of yarn skeins 5, 5 during the liquid or dyeing treatment.

10 To support the perforated tube or dyeing arm 3 in position over the container 1 and at the same time to supply liquid from the container to the perforated tube 3, a supply conduit 7 leads off from one end of the perforated tube and is connected with a suction pump 9 which in turn is connected by a conduit 11 with the interior of the container 1.

15 A skein rotating or advancing rod or arm 15 is supported at one end on the supply conduit 7 at a point adjacent the conduit's discharge end, and at its opposite end upon a dummy extension 17 of the perforated tube 3. With this arrangement, the skein advancing arm 15 lies parallel with and extends for the length of the perforated tube 3. To advance the skeins 5, 5 around the perforated tube support 3, the rod 15 is rotated around the tube through suitable rotatable mounting 18, 18 and pulley drive assembly 19. As desired, the rod may be intermittently rotated or rotated in a continuous manner.

20 As further seen in the drawing, there is provided a sleeve 22 which fits over the yarn skeins 5, 5. The sleeve 22 has inwardly tapering ends of flanges 24 which retain the skeins in place within the sleeve. The sleeve 22 is preferably formed of an impermeable, flexible material of a thermoplastic or fusible nature in the form 25 of plastic film or sheet material. The plastic sheet material may be transparent whereby the skeins may be observed by the operator. Regardless of the type of impermeable, flexible material used, this material must be 30 resistant to hot mild acids and strong hot alkali solutions maintained at temperatures up to 212° F. The material is inert to dyes or any coloring matter used to dye fabrics or yarns as processed by the cascade dyeing apparatus described above. In addition, the material must not become sticky or gummy as a result of processing characteristics or of the chemicals used. If these 35 limitations as to the material used are observed, the skein cover should have a useful life of several months in conditioned use. Some materials which can be used satisfactorily for forming the skein cover are natural and

40 synthetic rubbers, Saran type copolymers or terpolymers (polyvinylidene chloride) with or without acrylonitrile, alkyl methacrylates such as methyl methacrylate, polystyrene, etc. Certain types of polyethylene films may also be used. These are some of the materials which can 45 be used to form the skein cover.

46 As mentioned above, it is desirable, but not necessary, that the cover be made of a fusible material so that a heat fused seam 26 may be used to join the ends of the sheet material together to form a permanent non-leaking bond. Other types of seams such as sewn seams (if desired or required because of particular cover material used) may be used to join the ends of the sheet. If desired, the cover may be extruded or otherwise 50 formed in one piece, thus eliminating the necessity of forming a seam.

The cover for the skeins should extend approximately

four inches beyond (below) the yarn skeins in their suspended condition and the width should be such that it extends approximately the length of the dyeing arm 3.

In operation, the yarn skeins 5, 5 are first positioned over the perforated tube 3 and the skein advancing or rotating arm 15. The impermeable sleeve 22 is then positioned over the yarn skeins making certain that the end skeins are tucked in behind the tapered end portions 24 of the sleeve 22. After the desired dye liquor has been placed within the container 1, the suction pump 9 is put into operation thereby drawing liquid from the container and pumping it through the supply conduit 7 and into the perforated tube 3. From this point, the dye liquor passes through the perforations of the tube 3 under great pressure (64 gallons of dye liquor per minute) and strikes the filaments of the yarn skein in the form of strong jets. As the dye is applied to the yarn skeins 5, 5 in this manner, the skein advancing arm 15 is rotated either intermittently or continuously to move the skeins and the skein cover away from and around the perforated dye tube 3. The skeins are advanced in this manner until all portions of the yarn filaments have been exposed to the treating dye liquor.

One of the advantages which is prominent with the use of my new and novel skein cover is that a back pressure is set up with the dye liquor as it strikes the impermeable skein cover. This back pressure forces the dye liquor back through the coiled filaments of the skeins to provide thorough penetration of the yarn with the dye liquor within a minimum time. Since a back pressure is set up as described above, the yarn filaments are forced away from the cover as the dye liquor rebounds therefrom whereby the coiled filaments literally float through the dye liquor being partially spaced from the cover. This back pressure against the issuing dye spray also equalizes the volume of flow of the dye throughout the length of the dyeing arm and thus induces more level dyeing.

Since the cover is impermeable, the liquor can escape therefrom only at the ends of the sleeve. With this arrangement, a definite amount of dye liquor is retained within the sleeve at the bottom portion thereof to further assure adequate dye liquor for the coiled filaments as the skeins and cover are rotated about the dye tube 3.

A very important advantage of my invention is that the cost of skein dyeing is substantially reduced. The high cost of the chemicals used in skein dyeing constitutes a major part of the total cost for skein dyeing. Since the dyeing liquid is retained within my impermeable cover

to a much greater extent than with the permeable covers of the prior art, the amount of chemicals required is greatly reduced thus effecting a corresponding decrease in chemical cost. In addition, very little repeat dyeing is required with my apparatus which, of course, further reduces the cost of the operation.

Other advantages are found with the use of my skein cover in that broken filaments are eliminated and the coiled filaments do not become snarled or blown by the force of the dye spray during the dyeing operation. In view of these advantages, subsequent improved windability of the coiled filaments onto spindles and spools is provided.

While preferred embodiments of the invention have been shown and described herein, it is to be understood that changes and variations may be made without departing from the spirit and scope of the invention as defined in the appended claims.

I claim:

- 20 1. Yarn skein dyeing apparatus comprising a generally horizontally arranged pipe having perforations through which a dye liquor is forced under pressure so as to penetrate yarn skeins loosely looped thereabout, a flexible impervious tubular member looped about the pipe and adapted to cover the skeins with the skeins entirely between said pipe and said member, and said tubular member having inwardly directed flanges at the ends which form a basin at the bottom of the loop in which a pool of dye liquor is retained.
- 25 2. The invention set forth in claim 1 wherein said cover is formed of transparent plastic material.
- 30 3. The invention set forth in claim 1 wherein said cover is formed of rubber.
